[57] **ABSTRACT**

Deoxycytidine has been found to be a morphine antagonist. Morphine (heroin) addiction and toxification can be alleviated and combatted by administering deoxycytidine to the addicted or toxified subject. Satisfactory results are obtained by injecting deoxycytidine intra-peritoneally in the amount in the range 15-1200 mg/kg of body weight, depending on the subject.

6 Claims, No Drawings

METHOD OF COMBATTING MORPHINE ADDICTION AND TOXIFICATION

This invention relates to morphine addiction. More particularly, this invention relates to the treatment of morphine (heroin) addicts and to morphine detoxification.

Morphine (heroin) addiction is a serious social problem. In addition, morphine addiction is an ever present danger in medical practice when a morphine containing drug is administered to a patient to relieve pain. In view of the above, it is highly desirable for social and medical reasons to have available compositions and techniques employing the same useful in overcoming or combatting or alleviating morphine addiction, morphine toxification and combatting withdrawal symptoms experienced by morphine addicts and others upon withdrawal from morphine.

Accordingly, it is an object of this invention to provide a method of combatting morphine or heroin addiction. It is another object of this invention to provide a method of alleviating the withdrawal symptoms experienced by a morphine or heroin addict upon withdrawal from the morphine or heroin.

In at least one embodiment of the practice of this invention at least one of the foregoing objects will be achieved.

It has been discovered that deoxycytidine is a morphine antagonist. Deoxycytidine is employed as a morphine antagonist by administering deoxycytidine, preferably in a physiologically acceptable carrier, such as in a non-pyrogenic aqueous solution or suspension, to the subject suffering from morphine or heroin addiction or toxification or suffering from morphine or heroin withdrawal symptoms. Deoxycytidine is administered intraperitoneally, but other routes of administration may be employed, such as orally. Usually, an amount of deoxycytidine in the range about 15-1200 mg/kg of body weight of the subject being treated yields satisfactory results, although more or less may be employed. In the usual practice, an amount in the range 75-500 mg/kg, e.g. 100 mg/kg, would be employed.

In the practices of this invention it is preferred to employ deoxycytidine derived from mammalian DNA. Deoxycytidine is obtained from mammalian DNA by the breakdown of the DNA with pancreatic DNAase. The resulting breakdown products are then subjected to another enzymic treatment involving alkaline phosphatase to produce deoxycytidine and other deoxyribonucleosides. The resulting products are then chromatographically fractionated to yield deoxycytidine. In all of these steps the pH is held in the range from about 3.5 to about 9.

In these tests carried out to demonstrate the value and utility of the practices of this invention animals were employed. Animals, like man, are subject to morphine addiction and toxification and also experience withdrawal symptoms. The use of animal models in studies of morphine addiction is recognized and accepted and generally success in these animal studies point to and indicates a substantial equivalent success or effect in man.

In tests carried out in animals (mice) it was found that deoxycytidine antagonized the Straub effect and hyperactivity within about 2 or 3 minutes. In contrast the compound cytidine exhibited no activity. Deoxycytidine was shown to be effective in antagonizing the analgesic effect of morphine in rats as gauged by the

flinch-jump test. The naloxone-jump assay indicated the effectiveness and activity of deoxycytidine in detoxifying morphine treated mice.

In tests carried out to demonstrate the effectiveness of deoxycytidine as a morphine antagonist pairs of rats weighing about 300 grams each were injected intraperitoneally with morphine in an amount of about 20 mg/kg of animal body weight. The animals' response to graded shock was tested one half hour later, and the voltages required to elicit flinch and jump reactions were noted. Deoxycytidine in the amount 120 mg/kg of body weight was then injected into one of each of the pairs of the animals tested and the pairs were then tested again after one hour. The differences in shock strength required to elicit the flinch reaction were then determined. There was some decline in shock intensity which caused flinching normally occurring both in the morphine-treated controls and in the untreated animals. There was, however, a significant difference observed between deoxycytidine-treated morphinized animals and those which received morphine alone.

The naloxone jump assay is a measure of the severity of the withdrawal syndrome or degree of physical dependence on morphine. A significant difference ($p < 0.05$) in the number of naloxone-induced jumps shown by deoxycytidine-treated morphine tolerant-dependent mice compared with the untreated animals was observed.

The substitution of cytidine for deoxycytidine abolishes this mitigation of withdrawal symptoms. The effect is pharmacologically specific to deoxycytidine, which differs from cytidine only in one hydroxyl group of the molecule. Deoxycytidine in one massive dose thus acts as an effective detoxicant in morphine tolerant-dependent mice. Other tests shows that deoxycytidine effected a moderate stimulation of the depressed respiratory rate in a morphinized dog. Although there is a species variation in the response of morphine-treated animals to deoxycytidine, the tests shown deoxycytidine to be a morphine antagonist. For example, deoxycytidine when administered to a morphinized rabbit did not produce as great an increase in respiratory rate as in the dog.

The observed variability in response might be due to differences to tissue levels of endogenous factors involved or associated with deoxycytidine in its antagonist action. It is theorized that when the amount of these unknown factors are high or present, deoxycytidine acts effectively as an antagonist. At low levels, however, it may be that these low levels result in a show of less activity on the part of deoxycytidine as an antagonist.

The use of deoxycytidine as a morphine antagonist is especially attractive since it is non-toxic, non-addictive and a compound which can readily be prepared. These properties of deoxycytidine provide major advantages for the use of this compound as a morphine (heroin) antagonist for the treatment of drug addicts and morphine (heroin) detoxification. The fact that deoxycytidine is non-addictive and cellularly endogenous makes the subject or addict disposed to the administration of deoxycytidine in a treatment regime.

It is believed that the drug addict would have a more positive response with respect to treatment by deoxycytidine which stresses, in effect, the restoration of normal cell processes since deoxycytidine treatment

would be comparable or similar to vitamin or hormonal treatment.

In the test referred to hereinabove the quantitative determination of the antagonism of morphine analgesic action was performed with apparatus which delivers an electrical shock to rats [Evans, W. O., *Psychopharmacologia* 2:319 (1961)]. Strength of the shock was varied in steps by the operator; the equipment automatically delivers voltage to a grid housed in a box with a glass inset at the top. The shock occurred every 30 seconds for a one second duration. It was scrambled, that is, different bars in the grid are electrified each time so that the rat does not learn which are ground and which have applied voltage. The minimal strength of shock at which the animal flinches and at which it jumps was determined by successive up and down stepwise variations of shock strength.

In carrying out these tests morphine sulfate was injected intraperitoneally (IP) into rats at the dosage 20 mg/kg. The flinch level was determined $\frac{1}{2}$ hour later. Experience has shown that maximal effect of morphine occurs at this time and the literature reports that this time corresponds to the maximal concentration of morphine in the brain for this species under these conditions (Mule, S. J., in *Narcotic Drugs: Biochemical Pharmacology*, ed. D. H. Clouet, p. 106, Plenum Press, N.Y. 1971). As soon as the determination was completed, deoxycytidine, 120 mg/kg in saline solution, or saline, or cytidine, 128 mg/kg in saline solution was injected IP. The latter two solutions were controls. The flinch shock threshold was determined again after 1 hour. The controls normally showed a decrease in the shock strength required to elicit a flinch reaction due to decline in the morphine effect. The changes were compared with the changes in threshold for the deoxycytidine-treated animals using the unpaired Student *t* test. This standard statistical test gave $p < 0.01$, indicating a highly significant difference between the test group and controls, whether the latter are saline or cytidine.

Another experiment was carried out to show that deoxycytidine does not, of itself, affect the flinch threshold in normal animals. In this case, the changes in flinch threshold are small, since morphine was not injected and there was no wearing-off effect. It was found that deoxycytidine had no action on the flinch threshold in the non-narcotized rat. The observed changes were, therefore, due to its antagonism of morphine, not to a generalized stimulation. These data are summarized in accompanying Table 1.

TABLE 1

EFFECT OF DEOXYCYTIDINE TREATMENT ON CHANGE OF FLINCH THRESHOLD (VOLTS) IN MORPHINIZED AND CONTROL RATS

TREATMENT*	NO. ANIMALS	CHANGE IN FLINCH THRESHOLD**
Morphine-Deoxycytidine	8	10.9 $\pm$ 1.5
Morphine-Saline	8	5.1 $\pm$ 1.0
Morphine-Cytidine	5	5.6 $\pm$ 1.2
Saline-Deoxycytidine	5	1.5 $\pm$ .34
Saline-Saline	5	1.1 $\pm$ .42

* Rats injected IP with morphine sulfate, 20 mg/kg or with saline, flinch threshold determined $\frac{1}{2}$ h later. Animals then injected IP with deoxycytidine, 120 mg/kg saline, or cytidine 128 mg/kg, threshold tested again after 1 h.

** Mean $\pm$ s.e., $p < .01$ for difference between morphine-deoxycytidine group and controls; no significant difference in threshold changes between groups given saline followed by deoxycytidine or saline.

In many species morphine severely depresses respiratory rate. This is a major cause of death due to overdose in humans. Deoxycytidine will increase the rate of respiration in those morphine-treated animals which show this markedly lowered respiration in response to morphine. Deoxycytidine stimulates the respiration in both the morphine-treated dog and rabbit. The effect is more evident and prolonged in the former. This may, in part, be due to a species difference in response, but is probably also related to the dosages of morphine required to produce the lowered respiratory rate. In the dog, 4.9 mg/kg was injected IP, whereas 100 mg/kg was given the rabbits. It is known that the functions of cellular components other than deoxycytidine or deoxycytidine-containing compounds are affected by morphine (Dodge, P. W. and Takemori, A. E., *Biochem. Pharmacol.* 21:287, 1972). The apparent diminished efficiency of deoxycytidine in the rabbit may, therefore, actually result from morphine effects on other constituents of the cell due to the considerable dosage employed. In both species, deoxycytidine at approximately three times the weight of morphine was used for antagonism. In the dog, the morphinized respiratory rate was approximately doubled for the period of morphine action. In the rabbit, the increase was to about 50-75% of normal, varying over about 2 hours or from $\frac{1}{3}$ - $\frac{1}{4}$ of the duration of the morphine effect in this species.

An animal which can be shown to require morphine as a result of prolonged administration is termed tolerant-dependent to avoid anthropomorphic coloration. Standard procedures have been devised to induce this condition in various species. The mouse is most convenient and a schedule of increasing morphine dosage has been reported in the literature with a quantitative test for the degree of morphine dependence (Marshall, I. and Weinstock M., *Nature* 234:223, 1971).

Mice were injected IP daily for 8 days, starting at 50 mg/kg and increasing the dosage by this amount each day. On the eighth day, naloxone, 50 mg/kg, was given IP 4 hours after the morphine injection. Naloxone is a morphine antagonist which induces jumping in a morphine-dependent (or addicted) animal. The number of jumps in a standard period of time is a measure of the degree of dependence (addiction). If a separate antagonist were used prior to naloxone, its effectiveness is counter-acting the dependent (addictive) condition. 55 would be determined quantitatively by a reduction in the number of jumps. The overall procedure corresponds to the process of withdrawal in the human, so that a decreased number of jumps indicates an amelioration of the withdrawal symptoms. The foregoing is standard pharmacological interpretation. The results of such an assay are given in accompanying Table 2. Deoxycytidine given at a dosage of 3 times the weight of the final morphine injection significantly reduces the number of jumps by the treated group. It, therefore, acts to mitigate the withdrawal symptoms in this standard assay.

TABLE 2

NALOXONE INDUCED JUMPS IN DEOXYCYTIDINE-TREATED AND CONTROL MORPHINE-DEPENDENT MICE*

TREATMENT	NO. ANIMALS	NO. JUMPS**	p VALUE
Deoxycytidine	35	15 ± 3.8	<.05
Saline	31	29 ± 5.6	
Cytidine	10	29 ± 8.4	Not significant
Saline	10	38 ± 10.7	

* Male Swiss albino mice were injected IP with morphine sulfate, 50 mg/kg, dosage increased daily by this amount for seven days to the level of 400 mg/kg.

** Mean ± s.e. naloxone, 50 mg/kg, given IP alternately to individual animals of test and control groups 4 h after final morphine injection. Deoxycytidine, 1.2 gm/kg, cytidine 1.28 gm/kg or saline given to respective groups 2h before naloxone.

In other tests mice were injected IP with morphine sulfate at the level of 55 mg/kg. In about 5-10 minutes the tail of the mouse became raised upright or arched forward over the back. This is known as the Straub effect. At the same time the mice began to run aimlessly about the cage showing an extreme hyperactivity. This assay differs from the preceding one in that animals are not tolerant-dependent. It is termed an assay of the morphine acute effect. At this point deoxycytidine at the level of 165 mg/kg was injected. The mice began to become calm after 5-10 minutes and the upright tails returned to a normal position. In the next 2 hours, there were fitful spurts of morphine symptoms but, on the average, a qualitative difference in appearance and behavior was evident.

Other test data are set forth in accompanying Table 3.

TABLE 3

MILLIAMPERAGE FOR THRESHOLD FLICK*

	Initial	Final	Δ	
Test, Morphine + deoxycytidine	.882	.457	.425	40

Control, Morphine + H ₂ O	.898	.681	.217
Untreated	.463	.401	.062

NUMBER OF JUMPS IN EIGHT-MINUTES PERIOD AFTER NALOXONE INJECTION**

5	Test	(14)	13
	Control	(14)	28

* Six rats in each group, p <.02 for differences in values between test and control groups. The untreated group is included to indicate range of normal response. Its values are not included in calculation of significance.

10 ** Eight mice of the Test group and 3 of the Control group did not jump. Naloxone was given alternately to animals from the Test and Control Group, 1mg/20gm.

Application of the t test gives p < 0.02 for the difference in response between the two groups.

15 As will be apparent to those skilled in the art in the light of the foregoing disclosure, many modifications, alterations and substitutions are possible in the practice of this invention without departing from the spirit or scope thereof.

I claim:

20 1. A method for treatment of morphine addiction, or morphine toxicification and morphine withdrawal symptoms which comprises administering to the subject suffering the same an effective amount of a composition consisting essentially of deoxycytidine.

2. A method in accordance with claim 1 wherein the deoxycytidine is administered intraperitoneally.

3. A method in accordance with claim 1 wherein said deoxycytidine is administered intravenously.

30 4. A method in accordance with claim 1 wherein the deoxycytidine is administered in an amount in the range 15-1200 mg/kg per body weight per the subject.

5. A method in accordance with claim 4 wherein said deoxycytidine is administered in an amount in the range 100 mg/kg subject body weight.

35 6. A method in accordance with claim 1 wherein said deoxycytidine is administered in a non-pyrogenic aqueous physiologically acceptable carrier therefor.
